US00D949056S

(12) **United States Design Patent** (10) **Patent No.:** **US D949,056 S**
(45) **Date of Patent:** **** Apr. 19, 2022**

(54) **ELECTRIC BICYCLE**

(71) Applicant: **Beijing Niu Information Technology Co., Ltd.**, Beijing (CN)

(72) Inventors: **Yilin Hu**, Beijing (CN); **Chuankai Liu**, Beijing (CN); **Hao Yu**, Beijing (CN)

(73) Assignee: **Beijing Niu Information Technology Co., Ltd.**, Beijing (CN)

(**) Term: **15 Years**

(21) Appl. No.: **29/712,477**

(22) Filed: **Nov. 8, 2019**

(30) **Foreign Application Priority Data**

May 8, 2019 (CN) 201930221780.6

(51) **LOC (13) Cl.** **12-11**

(52) **U.S. Cl.**

USPC **D12/111**

(58) **Field of Classification Search**

(57) **CLAIM**

The ornamental design for an electric bicycle, as shown and described.

DESCRIPTION

FIG. 1 is a left side elevation of an electric bicycle embodying our new design;

FIG. 2 is a right side elevation view thereof;

FIG. 3 is a front elevation view thereof;

FIG. 4 is a rear elevation view thereof;

FIG. 5 is a top plan view thereof;

FIG. 6 is a bottom plan view thereof; and,

FIG. 7 is a front and left side perspective view thereof.

The broken lines shown in the figures depict portions of the electric bicycle that form no part of the claimed design.

1 Claim, 7 Drawing Sheets
